CORONALESS SHOCKPROOF UNIT

Montford Morrison, Montclair, N. J., assignor to
Westinghouse X-Ray Company, Inc., a corpora-
tion of Delaware

Application June 1, 1932, Serial No. 614,738

8 Claims. (Cl. 250—34)

My invention relates to shockproof apparatus utilized with discharge devices, such for example as X-ray tubes, which are subjected to relatively high potential electrical energy between the electrodes thereof without danger of possible shocks or disturbing noises which are detrimental to the operator or patient.

Apparatus of this general type are well known to the art and in such apparatus the high potential source of energy and the discharge device are usually immersed in a cooling and insulating medium within a metallic container. All the conductors and high tension terminals are thus immersed in the insulating medium which prevent contact thereof by operator or patient. By immersing the tube in the insulating and cooling medium it naturally follows that the requisite spacing between all high tension carrying parts can be materially lessened for the operating voltages of the tube than that normally required for the device operating in air at the same operating voltage, due to the higher dielectric strength of this liquid medium over a gaseous medium, such as air.

Objectionable features, however, exist in such apparatus in that upon failure of the X-ray tube requiring replacement thereof it is necessary to disconnect the conductors from the X-ray tube terminals while they are immersed in the oil and handle the oil coated tube. This at best is an unpleasant and time consuming task and usually requires the services of a skilled mechanic as the operator, who, is in most instances a Röentgenologist, is unfamiliar with these internal connections. Moreover, if failure of the device results in a puncture of the glass envelope causing particles thereof to fall upon the transformer it is necessary to drain off the insulating and cooling medium to remove all these particles.

A structure retaining all the advantages of these well known types of apparatus while obviating the objectionable features thereof has been disclosed in the copending application of W. A. McKay, Serial No. 572,785, filed November 3, 1931, and my present invention in its broadest aspect relates to such types of shockproof apparatus and is in the nature of an improvement thereon. In this particular structure the high tension source of energy is immersed in a liquid cooling and insulating material whereas the discharge device, such as an X-ray tube, is surrounded by a gaseous insulating material, such as air.

Although the shortest spacing, or normal ambient medium gap, between the electrodes of the

X-ray tube, measured outside the tube, is less than that required for the voltages at which the tube is designed to operate, the critical ambient medium gap or spark over distance between the electrodes of the tube is increased by means of insulating baffles to an extent as great, and preferably greater than, that required for the operating voltages of the tube. By the novel construction of this apparatus spark over between the terminals of the tube and all high tension parts is prevented resulting in a simple, compact, shock-proof unit.

In this particular apparatus, as shown in the above mentioned copending application, the X-ray tube is provided with certain baffles or electrical barriers which are intermeshed with the electrical barriers, forming part of a hollow open vase shaped receptacle for the X-ray tube.

This structure considerably increases the length of the free air gap sparkover distance or, as therein termed, "the critical ambient medium gap", between the anode stem, which projects outside the glass envelope of the X-ray tube, and the cathode connections. The envelope of the X-ray tube is effectively surrounded by an air spaced jacket and, around this jacket, is contained the oil immersing the high tension energizing transformer. Due to the difference in dielectric strength between the electrical barriers, the air-spaced jacket and the liquid dielectric immersing the transformer and surrounding the air-spaced jacket, the potential gradient at certain points in these various dielectric media is considerably increased resulting in the formation of corona at these points during operation of the device, which is annoying to operator and patient.

It is accordingly an object of my invention to fix the potential at or near the surface dividing the dielectric media so that the gaseous insulating medium surrounding the X-ray tube will not be overstressed and the formation of corona will be prohibited.

Another object of my invention is to provide a simple and compact X-ray apparatus which embodies an X-ray tube disposed in an ambient medium having a specific dielectric strength, with the source of high tension energy for energizing the tube disposed in an ambient medium having a higher dielectric strength than the ambient medium for said tube, in which a dielectric member separates the two ambient media and in which the formation of corona is prevented despite the difference in dielectric strength of the various ambient media.

Another object of my invention is to provide a shockproof X-ray apparatus embodying an X-ray tube surrounded by a gaseous insulating medium wherein the spacing between the electrodes thereof is insufficient to prevent spark over at the operating potential of the tube in which the spacing therebetween is increased upon insertion of the tube in the apparatus to prevent spark over during operation and in which the formation of corona is prevented.

A further object of my invention is the provision of a shockproof X-ray apparatus utilizing an X-ray tube having electrodes spaced apart a distance less than that required therefor when operating at its working potential in a gaseous insulating medium in which insulating baffles are employed of a higher dielectric strength than the gaseous insulating medium, to increase the critical ambient gap, to prevent spark over in that medium at the operating potential of the tube and in which the formation of corona is prevented despite the differences in dielectric strength of the various insulating media.

A further object of my invention is the provision of a shockproof X-ray apparatus employing an X-ray tube having electrodes spaced apart a distance less than that necessary when operating at the working potential of the tube in a gaseous insulating medium in which means are utilized having a higher dielectric strength than the gaseous insulating medium to increase the critical ambient gap to prevent spark over between the electrodes in a gaseous medium, at the operating potential of the tube, and in which the potential gradient at the points of greatest stress is materially reduced to prevent the formation of corona.

Still further objects of my invention will become apparent to those skilled in the art by reference to the accompanying drawing, wherein

Figure 1 is a cross sectional view of my novel X-ray apparatus in elevation showing diagrammatically the source of electrical energy therefor and all electrical connections, and

Figure 2 is a cross-sectional view of the structure of my apparatus shown in Fig. 1, taken on the line II—II thereof.

Referring now to the drawing in detail I have shown a metallic casing or tank 5, which contains a body of liquid insulating ambient material 6, such for example as oil. A cup-shaped member 7, composed of a suitable dielectric material, such as hard rubber, glass, porcelain or a phenolic condensation product, extends inwardly of the casing top and is thus surrounded by the liquid insulating medium therein. This cup-shaped dielectric member 7 has a cylindrical or conical wall 8 having a flange 9 extending outwardly therefrom at the upper end for the purpose of supporting the member in the casing 5 and also to form an oil tight seal therefor.

An electrical conducting socket 10 is molded or otherwise secured in the base of the dielectric member 7 and is provided with a suitable opening centrally disposed thereof into which extends a suitable heat conducting stem or rod 12. A cooling radiator 13 is rigidly secured to the lower extremity of this socket by means of a screw 14 and suitable washers 15.

The base of the cup-shaped dielectric member 7 is further provided with a pair of upwardly extending spaced concentric cylindrical baffle members 16 and 17, of the same material as the member 7, which may be molded integral therewith. These

baffles are of varying length, with the axes thereof in alignment with the stem 12 and opening in the conducting socket 10, for a purpose to be herein-after more fully set forth.

An X-ray tube 18, considerably shortened in length, is disposed interiorly of the cup-shaped dielectric member 7 and is of general cylindrical form with a substantially hemispherical upper end 19. The lower end of this X-ray tube is provided with a re-entrant sleeve 20 extending upwardly within and spaced from the main body portion of the X-ray tube. A metallic tubular sleeve member 22 is sealed to the upper portion of this re-entrant sleeve and in turn supports an anode 23 internally of the X-ray tube. This anode is arranged to engage the heat conducting stem 12 in any suitable manner, such for example, as threadedly engaging the latter or by the provision of a tapered recess portion of the anode engaging an upper reduced diameter, tapering extremity provided on the stem 12, which extends through the inner spaced surrounding cylindrical baffle 16, for the purpose of transmitting the heat from the anode to the cooling radiator 13. A tubular metallic skirt 24 is likewise supported by the sleeve 22 spaced therefrom, which extends downwardly below the glass-metal seal formed by the re-entrant sleeve 20 and the metallic sleeve 22.

A second re-entrant tube 25 is sealed internally of the X-ray tube 18 at a point slightly below the metal-glass seal and at its upper extending portion, the greater part of which is spaced from the walls of the tube 18, supports a spring sleeve 26 firmly secured to the anode, for the purpose of additionally supporting the anode and serving as a shock absorber. A glass cylinder 27, which may be suitably fused to the exterior of the X-ray tube, extends downwardly a substantial distance of the tube with the lower extremity thereof in alignment with the lower end of the tube.

A thermionic cathode (not shown) is provided interiorly of the tube 18 and the lead-in conductors therefor are secured to terminal caps 28 disposed exteriorly of the tube. A low tension transformer immersed in the liquid insulating medium and shown diagrammatically at 29 has its secondary winding 30 connected to these terminal caps 28 by means of a pair of conductors 32 and 33, one of which extends through an insulating bushing 34 in the wall of the cup-shaped member 7, and the other of which is suitably grounded to the casing 5 at 35, passing un-insulated through the wall of the member 7, for a purpose hereinafter explained.

A high tension transformer 36, also immersed in the liquid insulating medium, is provided with two secondary windings 37 and 38 connected in series for supplying high tension electrical energy to the main electrodes of the X-ray tube 18, through a conductor 39, which is connected to the anode 23 through the radiator 13, and a conductor 40, which is connected to the conductor 33 and thus grounded at 35, connects the secondary windings to the cathode.

The primary winding 42 of this high tension transformer 35, as well as the primary winding 43 of the low tension transformer 29, are arranged to be connected to a source of alternating current of the usual commercial potential (not shown) by having the supply conductors therefor extended exteriorly of the casing 5 in any suitable manner, such for example, as a terminal block (not shown).

In order to protect the X-ray tube 18 from breakage I provide the dielectric cup-shaped member 7 with a cap 44 formed of a phenolic condensation product or any other suitable material,

over the upper hemispherical end 19 of the tube which may be secured to the flange portion of the cup-shaped member. Although the cup-shaped member 7 and the oil within the casing absorbs substantially all stray X-radiation, a lead band 45 is preferably secured to the inner side of the cap 44 and extends slightly downwardly to overlap the upper portion of the cup-shaped member 7. The insulating bushing 34 prevents contact of the conductor 32 with the grounded lead band 45, whereas the conductor 33 passes uninsulated through the cup-shaped member 7 and lead band 45 to properly ground the latter to the casing 5.

The X-ray tube, as hereinbefore stated, is considerably shortened in length, i. e., the normal spacing or ambient medium gap between the electrodes measured outside the tube, as shown by the dotted line in Fig. 1, is insufficient to prevent spark over therebetween in the gaseous insulating medium, at the operating potential of the tube.

When, however, the tube is positioned within the cup-shaped member 7, the baffles 16 and 17, in cooperation with the glass cylinder or skirt 27 and the re-entrant stem 20, increase the critical ambient medium gap between the electrodes, as shown by the dot and dash line in Fig. 1, to an extent as great, and preferably greater, than that required for the maximum working voltage of the tube, consideration also being given to the usual inverse voltages normally attendant self-rectifying discharge devices, which sometimes exceeds the maximum working voltages by 50%, more or less. This increase of the critical ambient medium gap by the insulating medium of the baffles, together with the gaseous insulating medium, such as the air surrounding the tube, is thus sufficient to prevent spark over between the electrode terminals at the maximum operating potentials of the tube.

It is to be understood that although I have shown and described an X-ray tube, considerably shortened in length, which is operable at a potential above that required to cause spark over between the electrode terminals, wherein dielectric baffles are provided to increase the critical gaseous ambient medium gap to an extent, preferably greater than that required to prevent spark over between the electrodes, it follows that the X-ray tube may be operated at lower potentials without the necessity of these baffles or barriers, provided the spark over distance at these lower potentials is less than the normal spacing between the electrode terminals of the X-ray tube.

The portion of my invention thus far described is substantially analogous to that shown and described in aforementioned copending application of W. A. McKay.

In a device of this character, employing dielectric means of varying dielectric strength, it frequently happens that although actual spark over between the electrodes or between surfaces of opposite instantaneous polarity is prevented, corona may occur at points where the potential gradient is greatest. This may be appreciated when it is observed that between the grounded metallic wall of the casing 5, which carries one side of the high potential, and the cup-shaped member 7, a liquid dielectric is utilized.

On the other hand, between this cup-shaped member and the copper rod or stem 12 a gaseous insulating medium, such as air, is utilized with the baffles 16 and 17 interposed therebetween thus constituting two further insulating media of different dielectric strengths.

Although I have shown the high and low ten-

sion transformers 36 and 29 diagrammatically, in the actual embodiment of my invention the iron core of each, together with their respective windings, utilize substantially all of the spacing between the inner wall of the casing 5 and the cup-shaped member 7, in order to conserve space and make the entire unit as compact as possible.

The iron cores of these transformers are also grounded to the casing and thus carry ground potential with the spacing between them and the copper stem or rod 12 materially reduced, with the aforementioned dielectric media interposed therebetween. It can, therefore, be appreciated that a relatively strong electrostatic field is created with the potential gradient strongest at various points in the dielectric insulating members. For example, the potential gradient in the outer wall of the cup-shaped member 7 will be relatively large at points in close proximity to the grounded iron cores of the transformers and the copper anode stem or rod 12, which are designated at "A" in Fig. 1.

There is also a large potential gradient at points "B" in the outer cylindrical baffle 17 due to the electrostatic field and the difference in dielectric strength of this insulating baffle and the surrounding gaseous insulating medium, such as air. Likewise an equally strong potential gradient is imposed at points "C" in the inner cylindrical baffle member 16.

Although as before stated the spacing between the anode stem 12 and the high potential cathode terminal 28, with the X-ray tube in position, is great enough to make the critical ambient medium gap, as shown by the dot and dash line in the figure, sufficient to prevent spark over therebetween at operating voltages of the tube, the strong potential gradient at certain points in the various dielectric members may cause the formation of corona at these points.

In order to entirely eliminate the formation of corona I surround the cup-shaped dielectric member 7 with a metallic cylindrical sleeve or collar 50 of uniform diameter, or which may follow the contour of the tapering walls 8. This sleeve 120 constitutes a potential divider and extends a substantial distance longitudinally of the cup-shaped dielectric member 7 with the lower end preferably slightly below the latter member. The upper and lower ends of this sleeve are provided with a rounded edge 52, which may be rolled or otherwise suitably formed to obviate sharp edges and points. A plurality of insulated wedges, such as shown at 53, may be utilized to secure the sleeve member 50 about the lower periphery of the cup-shaped member, thus allowing a slight film of oil therebetween or, if desired, the sleeve may be rigidly affixed directly to the cup-shaped member.

In a similar manner smaller insulated wedges 54 may be employed at the upper end of the sleeve 135 member 50 to assist in securing the latter to the cup-shaped member.

For the purpose of reducing the potential gradient at the points of greatest stress in the various dielectric members, namely A, B, and C, I connected this potential dividing sleeve 50 to the secondary winding of the high tension transformer 36 by means of a conductor 55. Although in the embodiment of my invention, shown in the accompanying drawing, I have shown the conductor 145 55 connected to the mid-point between the two secondary windings 37 and 38, and substantially one half the total output potential of these windings is impressed between the sleeve 50 and both the anode and ground, thus substantially divid-

145

150

ing the total potential between the sleeve and ground, it is to be understood that this is not essential.

The conductor 55 may just as readily be connected to any point of either of the secondary windings 37 or 38. The proper point of connection and the potential impressed upon the sleeve member 50 varies under different conditions. For example, the operating potential of the X-ray tube is the salient factor that controls the requisite potential which must be applied between the sleeve 50 and the anode stem 12 to prevent the formation of corona. It necessarily follows that the greater the operating potential of the tube the greater the potential which must be impressed upon the sleeve 50.

In applying a given potential to this sleeve 50 the potential gradient at the points of greatest stress in the various dielectric insulating media are reduced in proportion to the difference between the total output potential of the entire secondary winding of the high tension transformer and that between the sleeve 50 and the anode stem 12.

In impressing a predetermined definite potential upon the sleeve 50 the potential gradient at the normal points of greatest stress, namely A, B and C, will be no greater than the potential between the anode stem 12 and the sleeve 50. The operating potential of the X-ray tube and the length of the critical ambient medium gap required to prevent spark over between the electrodes of the tube is accordingly immaterial and does not affect the potential gradient, which as previously mentioned, is fixed by the sleeve 50.

This may be best appreciated by assuming given potential values. Assuming, therefore, that the total operating potential of the X-ray tube and consequently the output of the secondary windings is 100 k.v. with the sleeve 50 connected, by means of conductor 55, to the midpoint between these windings, as shown in the figure, a potential of one-half the total operating potential of the tube is thus impressed between the sleeve 50 and the anode stem 12, and between the former and the grounded casing 5. The electrostatic field and the stress upon the various dielectric insulating media is accordingly reduced by a reduction in potential between sleeve 50 and anode stem 12 to 50 k.v. The points in these various dielectric media of greatest potential stress are likewise reduced to a value of 50 k.v. which is more than sufficient to prevent the formation of corona at these points.

If now the conductor 55 is connected to either one of the respective windings in such a manner that, with the operating potential of the X-ray tube being 100 k.v., only 40 k.v. is impressed between the sleeve 50 and the anode stem 12, while 60 k.v. is impressed between the sleeve 50 and ground. Again the potential gradient at the points of greatest stress in the dielectric insulating media is reduced to a potential which is sufficient to prevent the formation of corona at these points.

It naturally follows that there is a certain minimum beyond which the potential impressed upon the sleeve 50 cannot be reduced at a given operating potential of the X-ray tube without corona forming at the points of greatest potential stress in the dielectric media. This, as before stated, depends primarily on the operating potential of the X-ray tube and with a lowering of the same this minimum potential necessary for the sleeve 50 is also lowered.

Moreover, it is not essential that the potential dividing sleeve 50 be connected to the high voltage source by a conductor as it will assume a definite potential under operation. In order, however, for this sleeve to assume a requisite potential sufficient to prevent the formation of corona the various parts must be properly proportioned. The liquid dielectric surrounding the high tension transformer 36 and the cup-shaped member 7 has a specific dielectric strength as well as the gaseous insulating medium surrounding the X-ray tube. A difference in dielectric strength likewise exists in the baffles or barriers 16 and 17, as before stated. This, therefore, causes these various dielectric media to act in a manner analogous to condensers connected in series, i. e., the casing wall and the member 7 constitutes one condenser and the latter member, together with the tube surrounded by the gaseous insulating medium, constitutes the other condenser.

However, as two dielectric media are involved, which differ in dielectric strength, the capacity effect of the same also differs. In the same manner as with condensers, therefore, the potential thereof will vary inversely proportional to the capacity.

For example, the liquid insulating medium having the largest capacity effect will cause a greater potential stress to be electrostatically impressed upon the interior of the cup-shaped member 7 and the baffles 16 and 17 than upon the casing walls and the exterior of the cup-shaped member 7, in contact with the oil. The potential divider sleeve 50 being positioned as a plate in one of these fictitious condensers will, therefore, assume a definite potential by induction from the source of energy for the tube.

In order for this potential to be inductively impressed upon the sleeve 50 sufficiently great enough to prevent the formation of corona, as before mentioned, during operation of the device its spacing relative to the cup shaped member must be apportioned to the operating potential of the X-ray tube and the capacity effect created by the gaseous insulating medium forming the remaining fictitious condenser. This can, however, be readily calculated or may be done empirically until there is an entire absence of the formation of corona at the maximum operating potential of the X-ray tube.

It thus becomes obvious to those skilled in the art that I have provided a novel shockproof unit utilizing an X-ray tube in a gaseous insulating medium, considerably shortened in length, wherein the spacing or normal ambient medium gap between the electrodes is less than that required at the operating potential of the tube in that medium and in which the critical ambient medium gap is rendered sufficient to prevent spark over between the electrodes by the utilization of dielectric insulating media of varying dielectric strength and the formation of corona is entirely prevented.

Moreover, the potential gradient at the points of greatest stress in the various dielectric media is reduced to such an extent that the formation of corona at these points is prohibited.

Although I have shown and described one specific embodiment of my invention I do not desire to be limited thereto as various other modifications of the same may be made without departing from the spirit and scope of the appended claims.

What is claimed is:

1. In an X-ray apparatus the combination of a casing, an electrical discharge device having

- an envelope and electrodes spaced apart and disposed in an ambient dielectric medium, means disposed in said casing in a second ambient dielectric medium in juxtaposition with said discharge device for energizing said discharge device and having portions thereof in close proximity to the latter, dielectric means disposed between said discharge device and said first mentioned means to prevent contact of the respective ambient dielectric media for each and forming a compartment for housing said discharge device, and means disposed in the shortest path between said dielectric means and said first mentioned means to reduce the potential gradient upon said dielectric means and the ambient dielectric medium for said discharge device and said first mentioned means, respectively, at points of greatest potential stress, and to prevent the formation of corona between said discharge device and all parts of said first mentioned means disposed in close proximity to said discharge device. 5 80
2. In an X-ray apparatus the combination of a casing, an electrical discharge device having an envelope and high tension electrode terminals spaced apart a distance less than that required to prevent spark over therebetween at the operating potential of said device, means carried by said casing and cooperating with said discharge device to increase the spark over distance between the electrodes of said device to an extent at least as great as that required to prevent spark over therebetween at the maximum operating potential of said device and forming a housing for said discharge device, means in said casing in juxtaposition with said first mentioned means and connected to said discharge device for energizing the same, and means associated with both of said aforementioned means to prevent the formation of corona about said first mentioned means and said discharge device. 10 85
3. In an X-ray apparatus the combination of a casing, an electrical discharge device disposed in an ambient dielectric medium and having an envelope and electrodes spaced apart a distance less than that required to prevent spark over therebetween at the operating potential of said device in said ambient medium, a second ambient dielectric medium in said casing having a higher dielectric strength than said first mentioned ambient medium cooperating with the latter and said discharge device to increase the spark-over distance between the electrodes of said device to an extent at least as great as that required to prevent spark over at the maximum operating potential of said device and forming a housing for said discharge device, means disposed in said casing in a third ambient dielectric medium in juxtaposition to said second mentioned ambient dielectric medium and connected to said discharge device for energizing the latter, and means connected to said last mentioned means and surrounding said second mentioned ambient dielectric medium to reduce the potential gradient in all of said ambient dielectric media at points of greatest potential stress and to prevent the formation of corona between said discharge device and all said ambient dielectric media. 15 90
4. In an X-ray apparatus the combination of a casing, an electrical discharge device disposed in a gaseous dielectric insulating medium and having an envelope and high tension electrode terminals spaced apart a distance less than that required to prevent spark over therebetween at the operating potential of said device, a solid insulating medium in said casing having a higher dielectric strength than said gaseous insulating medium cooperating with said discharge device and said gaseous insulating medium to increase the spark over distance between the electrodes of said device to an extent at least as great as that required to prevent spark over at the maximum operating potential of said device and forming a housing for said discharge device, a high tension transformer in said casing immersed in a liquid insulating medium in juxtaposition with said solid insulating medium and connected to said discharge device for energizing the latter, and means disposed between said high tension transformer and surrounding said solid insulating medium to reduce the potential gradient in all said dielectric media at points of greatest stress and to prevent the formation of corona about said discharge device. 20 95
5. In an X-ray apparatus the combination with a transformer casing, a high tension transformer contained therein and an ambient dielectric medium for said transformer, of a dielectric member extending into said casing in proximity to said transformer and forming a separate compartment provided with a gaseous ambient dielectric medium, a discharge device mounted in the ambient medium within the compartment formed by said dielectric member and connected to said transformer for energization by the latter, and means disposed in said casing between said transformer and said dielectric member to reduce the potential gradient in said dielectric member and the ambient dielectric media for said transformer and discharge device and to prevent the formation of corona during operation of said apparatus. 25 100
6. In an X-ray apparatus the combination with a transformer casing, a high tension transformer contained therein and an ambient dielectric medium for said transformer, of a dielectric member extending into said casing in proximity to said transformer and forming a separate compartment provided with a gaseous ambient dielectric medium, a discharge device mounted in the ambient medium within the compartment formed by said dielectric member and connected to said transformer for energization by the latter, and a metallic shield disposed in said casing between said transformer and said dielectric member and connected to the former to reduce the potential gradient in said dielectric member and the ambient dielectric media for said transformer and discharge device and to prevent the formation of corona during operation of said apparatus. 30 105
7. In an X-ray apparatus the combination with a transformer casing, a high tension transformer contained therein and an ambient dielectric medium for said transformer, of a dielectric member extending into said casing in proximity to said transformer and forming a separate compartment provided with a gaseous ambient dielectric medium, a discharge device mounted in the ambient medium within the compartment formed by said dielectric member and connected to said transformer for energization by the latter, and a metallic shield disposed in said casing between said transformer and said dielectric member, said metallic shield connected to said transformer to impress a potential thereupon less than the operating potential of said discharge device to reduce the potential gradient in said dielectric member and the ambient media for said transformer and discharge device, at points therein of greatest potential stress, to prevent the formation of corona 35 110

about said discharge device during operation of said apparatus.

8. In an X-ray apparatus the combination with a transformer casing, a high tension transformer contained therein and an ambient dielectric medium for said transformer, of a dielectric member extending into the ambient medium for said transformer in proximity to the latter and forming a separate compartment provided with a gaseous ambient dielectric medium, a discharge device mounted in the ambient medium within the compartment formed by said dielectric member and connected to said transformer for energization by the latter, and means disposed in said

casing between said transformer and said dielectric member, said means comprising a metallic shield connected to said transformer to form an electrostatic field less than the electrostatic field normally formed between said discharge device and said transformer to reduce the potential gradient in said dielectric member and the ambient dielectric medium for said transformer and discharge device at points therein of greatest potential stress and to prevent the formation of corona about said discharge device during operation of said apparatus.
